The ornamental design for a shoe upper, as shown and described.

DESCRIPTION

FIG. 1 is a front perspective view of a shoe upper showing my new design;

FIG. 2 is a side view thereof; and,

FIG. 3 is a rear perspective view thereof.

The broken line immediately adjacent to the shaded area represents an unclaimed boundaries of the design. The unshaded regions within the shaded area form no part of the claimed design. The broken lines showing of the five circular regions, the five oval shaped regions, and the remainder of the shoe are for environmental purposes only and form no part of the claimed design.
